United States Patent Office

Des. 203,964
Patented Mar. 8, 1966

203,964

APPLIQUE

Bettye J. Klauss, 321 Jackson Ave., Evansville, Ind.

Filed Feb. 12, 1965, Ser. No. 83,807

Term of patent 14 years

(Cl. D3—9)

FIG. 1.

FIG. 2.

FIG. 3.

The bottom of the applique, opposite the top shown in FIGURE 1, is plain and unornamental.

The essential features of my design reside in the portions shown in solid lines.

I claim:

The ornamental design for an applique as shown and described.
